UNITED STATES PATENT OFFICE.

CHARLES P. EISENHAUER, OF DAYTON, OHIO, ASSIGNOR TO THE DURO COMPANY, OF DAYTON, OHIO, A CORPORATION OF OHIO.

PUMP.

Application filed February 28, 1927. Serial No. 171,516.

My invention relates to pumps and in particular to valves therefor.

It is the object of my invention to provide a valve system which will permit of ready and quick escape of liquid from a pump having rapidly reciprocating pistons without objectionable noise or shock. The primary problem in the operation of small rapidly reciprocating pistons in a plurality of cylinders particularly for use in domestic pumps is the elimination of hammering and of valve noise.

My invention accomplishes this object.

Referring to the drawings: Figure 1 is a section through the cylinder casing, piston, valve mechanism and exit casing showing the parts in intake position with the piston and piston rod in the extreme right hand position;

Figure 2 is a view of the parts in intermediate or balanced position;

Figure 3 is a view in ejecting position with the piston rod and piston in the extreme left hand position.

Referring to the drawings in detail, 1 is a cylinder casing which has a lining 2 for the cylinder 3 in which operates a piston rod 4 and a piston 4^a. This piston may be of any desired construction but the one I have shown is preferable. On the end of the casing 1, which contains an inlet opening 5 and an inlet chamber 6, is a plate 7 having an inlet passageway 8 communicating with the inlet passageway or chamber 6 in the cylinder housing 1. This ring is joined by a gasket 9 to the casing 1. Within the ring 7 is mounted a stationary cylinder designated 10 having an end plug or closure 11 which engages with the interiorly disposed helical spring 12. This spring has its other end mounted within an apron 13 of a slide valve 14 that reciprocates within the cylinder 10. This piston is formed not only with the apron 13 but with a partition 15 on the other side of which is a second apron 16.

The apron 16 is provided with a plurality of radial apertures 17 which are adapted to register with ports 18 in the wall of the cylinder 10, such ports 18 communicating with the inlet chamber 8 in the ring 7.

Any fluid which may be trapped in the space 19 behind the partition 15 of the slide valve 14 can drain through the opening 20 into a channel 21 which communi-

cates with the inlet passageway 8. The radial apertures 17 are also adapted to communicate with the exit passageways 22 in the wall of the cylinder 10, which passageways communicate with the exit chamber 23 in the exit casing 24. The exit casing is sealed to the ring 7 by the gasket 25^a, the whole being kept together by bolts such as 26.

Method of operation.

When the piston rod 4 and piston 5 move to the right hand direction, the suction or vacuum thereby created serves to move the piston 14 to the right hand against the resistance of the spring 12 bringing the ports 17 in register with the ports 18, permitting the entrance of fluid through the entrance passageway 5, chamber 6 and passageway 8 into the interior of the slide valve 14 on the right hand of the partition 15 within the apron 16 and in the forward end of the cylinder 3.

Upon the reversal of direction of movement of the piston rod 4 and the piston 5, the fluid so collected within the forward end of the cylinder 3 is compressed, with the result that the slide valve 14 is moved to the left hand against the resistance of the spring 12 until the ports 17 are in registry with the ports 22 so that the compressed fluid may make its exit into the exit chamber 23 and out through the exit passageway 25.

It will be understood that I desire to comprehend within my invention such modifications as may be necessary to adapt it to varying conditions and uses.

Having thus fully described my invention, what I claim as new and desire to secure by Letters Patent, is:

1. In combination, a cylinder, a piston and piston rod, said cylinder having exit and intake ports, a slide valve mounted in one end of said cylinder, yielding means for maintaining said slide valve in a predetermined position, said slide valve having a registering port adapted to register with the inlet and exit ports in the cylinder whereby alternate compression and suction set up in said cylinder by said piston will move said slide valve to register the position for intake and exit of the fluid.

2. In combination, a cylinder in a cylinder casing having an intake passageway opening into an intake chamber, a piston

and piston rod in such cylinder, said cylinder having an intake port adapted to register with said intake passageway chamber and an exit port adapted to register with a chamber in an exit casing, an exit casing, a slide valve in one end of said cylinder having a port adapted to register alternately with the inlet and exit port in the cylinder, and yielding means for maintaining said slide valve in a normal position.

3. In combination, a cylinder in a cylinder casing having an intake passageway opening into an intake chamber, a piston and piston rod in such cylinder, said cylinder having an intake port adapted to register with said intake passageway chamber and an exit port adapted to register with a chamber in an exit casing, a slide valve in one end of said cylinder having a port adapted to register alternately with the inlet and exit port in the cylinder, and yielding means for maintaining said slide valve in a normal position, and means for draining any accumulation of liquid behind said slide valve into said inlet passageway.

4. In combination, a cylinder in a cylinder casing having an intake passageway opening into an intake chamber, a piston and piston rod in such cylinder, said cylinder having an intake port adapted to register with said intake passageway chamber and an exit port adapted to register with a chamber in an exit casing, a slide valve in one end of said cylinder having a port adapted to register alternately with the inlet and exit port in the cylinder, and yielding means for maintaining said slide valve in a normal position, said cylinder having inlet and exit ports with the slide valve being of lesser diameter than the diameter of the portion of the cylinder containing the piston.

5. In combination, a cylinder having one portion for receiving a piston and piston rod and a second portion for guiding a slide valve, a slide valve consisting of oppositely disposed aprons and a central partition, yielding means between said central partition and the end of said cylinder, said

cylinder having an inlet port and an exit port adapted to register with a port in one apron of said slide valve.

6. In combination, a cylinder having one portion for receiving a piston and piston rod and a second portion for guiding a slide valve, a slide valve consisting of oppositely disposed aprons and a central partition, yielding means between said central partition and the end of said cylinder, said cylinder having an inlet port and an exit port adapted to register with a port in one apron of said slide valve, a ring adapted to form a passageway around said cylinder for communicating with its inlet port and to communicate with an entrance passageway in the cylinder casing, and an exit casing surrounding the end of said cylinder for receiving fluid from its exit port whereby the suction and compression set up in the cylinder will move said slide valve for the control alternately of the inlet and exit of fluid.

7. In combination, a cylinder having inlet and exit ports, a piston and a piston rod operating in the said cylinder a slide valve in the said cylinder controlling the said ports, yielding means adapted to normally position the said slide valve in a predetermined position, the said yielding means and the said slide valve acting in co-operation with the movement of the piston and piston rod to control the inlet and exit fluid to and from the cylinder and to cushion the shock of movement of the said fluid.

8. In combination, a cylinder having inlet and exit ports, a piston and a piston rod operating in the said cylinder, a yieldingly controlled shock absorbing slide valve in the cylinder controlling the said ports and normally positioned in a predetermined position, means for yieldingly controlling the slide valve, the said slide valve acting in co-operation with the movement of the piston and piston rod to control the inlet and exit fluid to and from the cylinder and to cushion the shock of movement of the said fluid.

In testimony whereof, I affix my signature.

CHARLES P. EISENHAUER.
